CARTRIDGE FUSE

Lewis Detch, Pittsburgh, Pa.

Application March 20, 1952, Serial No. 277,687

4 Claims. (Cl. 200—131)

1

This invention relates to electric circuit breakers, particularly thermal circuit breakers and more especially to fusible element thermal breakers.

A principal object of this invention is to provide a knife blade cartridge fuse which is so constructed that all current carrying parts are associated in one assembly which may be inserted in and withdrawn as a whole from a cartridge provided with metallic end ferrules without the use of end ferrule caps.

A further object of the invention is the construction of a cartridge fuse of the kind specified which includes an insulating stationary bar for separating knife blades which includes means for preventing undue wear upon the end surfaces of the spacer bar.

Other objects and advantages will appear as the description of the particular physical embodiment selected to illustrate the invention progresses and the novel features will be particularly pointed out in the appended claims.

In describing the invention in detail and the particular physical embodiment selected to illustrate the invention, reference will be had to the accompanying drawings and the several views thereon, in which like characters of reference designate like parts throughout the several views, and in which:

Figure 1 is a side elevational view of a knife blade cartridge fuse embodying my invention; Fig. 2 is a cross sectional view of the device as shown by Fig. 1 on a plane parallel to the broad faces of the knife blades; Fig. 3 is a cross section of the device of Fig. 1 on a plane at a right angle to the plane upon which Fig. 2 is taken; Fig. 4 is a cross section of the device of Fig. 1 in a plane parallel to the broad faces of the knife blades but viewed in a direction 180° from the direction in which Fig. 2 is viewed.

My improved knife blade fuse includes a cartridge 1 of insulating material, preferably horn fibre.

My invention utilizes two metallic end ferrules, one on each end of the cartridge 1, as 3 and 5. These end ferrules may be made of any suitable or appropriate metal, preferably brass. They may be attached to the cartridge 1 in any suitable or preferred manner. I have illustrated them as secured by matching threads, as 7, and with the additional security of a threaded screw 9 passing through the ferrule and into the material of the cartridge 1. Of course, I do not mean to exclude by the use of a screw 9, the use of a through rivet headed on both ends. I do not mean to exclude by the showing the use of an unthreaded cap.

2

The ferrule 5 is provided with an internal shoulder 11. The ferrule 3 is provided with an internal thread 13.

All of the other parts of my fuse are embraced within what I call the knife blade assembly which includes two knife blades, one 15 at one end and the other 17 at the other end.

The knife blade assembly includes a stationary bar 19 of insulating material. This may well be made of horn fibre.

At each end of the spacer bar 19 I provide a butt plate as 21 and 23. Each of these butt plates has a flat plate-like portion as 25 and right angle extensions at each end, as 27 and 29. The right angle extension 27 seats on the end of the spacer bar. The right angle extension 29 seats on the end of a knife blade. Each of the butt plates is firmly attached to the stationary bar 19 by through rivets, as 31 and 33.

Each of the knife blades embraces two rectangular portions. Knife blade 15 has the rectangular portions 35 and the tang end portion 37. As one end of the knife blade is a tang end portion, the butt plates, as 21, are interposed between the tang ends of the knife blades and the spacer bar 19, and the right angle portion, as 29, bears against the end of a tang end.

The spacer bar, the butt plates and the tang ends are each formed with through bores, as 39 and 41. Within the through bores, there are positioned threaded bolts 43 and 45. The threaded bolts are each provided with a washer, as 47 and a nut, as 49. By means of the bolts 43 and 45 and the nuts and washers as 47 and 49, the fusible link 51 is positioned spanning the tang ends of the knife blades and is held securely in position by the nuts and washers so that a firm unitary self-assembly is made of the spacer bar 19, the butt plates 21 and 23, the knife blades 15 and 17, the fusible link 51 and the bolts 43 and 45 together with their washers, as 47 and nuts, as 49.

On knife blade 15 between the shoulders 53 and 55 and the right angle portion 27 of the butt plate 21 is positioned a metallic cup 57. This metallic cup 57 is formed with a shoulder 59 to cooperate with the shoulder 11 of the ferrule 5 and with a peripheral surface 61 of an external diameter proper to centralize the metallic cup 57 in the through orifice 63 of the end ferrule 5. The metallic cup 57 is also provided with a peripheral surface 65 which just fits the internal bore 67 of the end ferrule 5. This peripheral surface is covered with criss-cross ridges and depressions, that is, it is knurled. The object of this knurling is to provide a surface which will tend to catch and hold vaporized fusible strip metal.

The metallic cup 57 is also provided with through vent bores, as 69 and 71. In addition, a metallic washer 73 is provided with a slot 75 embracing the tang 37 and positioned over the vents 69 and 71 and between the metallic cup 57 and the butt plates, as 21.

As will be hereinafter more fully described, there are means associated with the other end of the cartridge fuse by which the metallic cup 57 is forced firmly against the shoulder 11 of the ferrule 5 and the spacer bar 19 with the butt plate 21 is forced firmly against washer 73 and washer 73 is forced firmly against the inside of the cup 57.

At the other end of the fuse from knife blade 15, is knife blade 17 and on the tang 71 thereof is another metallic cup 79 formed with a slot 81 embracing the tang 71 and positioned between the shoulders 83 and 85 and the right angle member 87 of the butt plate 23. The metallic cup 79 is provided on a portion of its periphery with threads 89 cooperating with threads 13 on the end ferrule 3. The cup 79 is also provided with two vents, 91 and 93.

The metallic washer 95 is provided with the slot 97 embracing the tang 71 and is interposed between the metallic cup 79 and the right angle portion 87 of the butt plate 23.

Cup 79 by means of thread 89 may be screwed firmly into the end of the ferrule by cooperation with the thread 13 on the ferrule 3. When this is done, the washer 95 bears firmly against the butt plate 23 and the cup 79 bearing against the washer 95 forcing all the parts toward the right, as viewed in Fig. 3, so that cup 57 bears tightly against the shoulder 11 on the other end of the cartridge. In order to facilitate the cooperation of threads 39 and 13, the end wall 99 of the metallic cup 79 is extended outwardly to have an external diameter greater than the diameter of the adjacent ferrule 3 and the peripheral surface is knurled as shown most clearly in Fig. 1 at 101. This knurling not only provides a convenient and efficient means for assembling the parts, but it also serves as an indicator so that one about to take the fuse apart knows that the thread is at that end where the knurling 101 is and so knows from that in what direction to turn the assembly in order to remove the assembly from the cartridge. Previous two-piece cartridges have been deficient in this respect as it has been left for the user to ascertain, by trial, which direction a particular knife blade should be turned in order to release the knife blade assembly from the cartridge.

From the hereinbefore given description, it will now be apparent that I have provided a knife blade cartridge fuse in which there are, in effect, two main parts, a fusible strip assembly, and a cartridge. When one is to replace the fusible strip in such a fuse, there are only two main parts to handle so that there is no real danger of losing an essential part. After the fuse strip assembly has been separated from the cartridge, the nuts, as 49, merely have to be loosened and the fuse strip is so formed that its ends may be slipped thereunder, and then the nuts, as 49, are tightened so that there is no danger of losing such small parts.

The provision of the knurled periphery 65 on the metal cup 57 provides a means whereby when a fusible link, as 51 is volatilized, the vaporized metal which tends to issue from the right hand end of the fuse, as viewed in the figures, will be largely caught by the knurled surface 65.

Venting is also provided for in the two vents as 69 and 71 at the right hand end of the fuse.

At the left hand end of the fuse, as viewed in the figures, vents 91 and 93 provide good release. In addition, however, there is always venting through the associated screw-threads 13 and 89 and for this reason, a space is provided at 103 so that good escape is provided as soon as the hot gases and metal vapor have traversed the threads 13 and 89.

It should also be noted that when the fuse is properly assembled, there are spaces showing on each end of the fuse between the metallic cups on each end and the shoulders of the knife blades, that is, the spaces 105 and 107 are clearly evident if the fuse has been properly assembled tightly in position in the cartridge.

Although I have particularly described one particular physical embodiment of invention and explained the construction and principle thereof, nevertheless, I desire to have it understood that the form selected is merely illustrative, but does not exhaust the possible physical embodiments of the idea of means underlying my invention.

What I claim as new and desire to secure by Letters Patent is:

1. A fuse strip carrier and knife blade assembly, including, in combination, a spacer bar of insulating material, two metallic knife blades, one at each end of the spacer bar, each knife blade formed of two rectangular portions, one narrower than the other forming a tang end and a shoulder, one tang endlapping over one end of the spacer bar and the other tang endlapping over the other end of the spacer bar, metallic butt plates, one at each end of the spacer bar interposed between the tang end of a knife blade and the spacer bar, each butt plate formed with a flat plate portion contacting a tang end on one side and the spacer bar on the other, said butt plates each having two right angle portions, one at each end, one right angle portion directed in one direction and the other right angle portion in an opposite direction, one right angle portion on one butt plate abutting the end of the spacer bar and the other right angle portion on the same butt plate abutting the end of a tang, two rivets, one adjacent each end of the spacer bar, each rivet passing through the spacer bar and a butt plate and attaching the butt plate firmly to the spacer bar, said spacer bar formed with two through bores, one adjacent each end, each tang and each butt plate also formed with a through bore aligning with the through bores at each end of the spacer bar respectively, two screw threaded bolts, one positioned in each of the through bores of the spacer bar and passing through a tang end and a butt plate, two nuts and two washers, one of each on each of the bolts whereby a fuse link provided with a through bore in each end is attached spanning the space between tang ends, a metallic cup shaped member positioned on one tang between the adjacent shoulder and the adjacent spacer bar end, said metallic cup formed with a slot there-through receiving the tang end with an external shoulder adapted for contact with an internal shoulder of a cartridge end ferrule and with a knurled outer periphery of a diameter adapted to make a close fit in a cartridge end ferrule internal bore adjacent inwardly of the said internal shoulder of a cartridge end ferrule, said metallic cup further formed with vent bores therethrough and a metallic washer formed with a through slot positioned on the tang between the metallic cup and the end of the spacer bar

covering the said vent bores and means on the other tang for securing the assembly in a cartridge with the metallic cup pressed tightly against the said internal shoulder of an end ferrule.

2. A fuse strip carrier and knife blade assembly, including, in combination, a spacer bar for insulating material, two metallic knife blades, one at each end of the spacer bar, each knife blade formed of two rectangular portions, one narrower than the other forming a tang end and a shoulder, one tang endlapping over one end of the spacer bar and the other tang endlapping over the other end of the spacer bar, metallic butt plates, one at each end of the spacer bar interposed between the tang end of a knife blade and the spacer bar, each butt plate formed with a flat plate portion contacting a tang end on one side and the spacer bar on the other, said butt plates each having two right angle portions, one at each end, one right angle portion directed in one direction and the other right angle portion in an opposite direction, one right angle portion on one butt plate abutting the end of the spacer bar and the other right angle portion on the same butt plate abutting the end of a tang, two rivets, one adjacent each end of the spacer bar, each rivet passing through the spacer bar and a butt plate and attaching the butt plate firmly to the spacer bar, means for positioning and securing the assembly in a cartridge, and means for attaching a fusible link between the tang ends.

3. A fuse strip carrier and knife blade assembly, including, in combination, a spacer bar of insulating material, two metallic knife blades, one at each end of the spacer bar, each knife blade formed of two rectangular portions, one narrower than the other forming a tang end and a shoulder, one tang endlapping over one end of the spacer bar and the other tang endlapping over the other end of the spacer bar, metallic butt plates, one at each end of the spacer bar interposed between the tang end of the spacer bar and a knife blade and the spacer bar, each butt plate formed with a flat plate portion contacting a tang end on one side and the spacer bar on the other, said butt plates each having two right angle portions, one at each end, one right angle portion directed in one direction and the other right angle portion in an opposite direction, one right angle portion on one butt plate abutting the end of the spacer bar and the other right angle portion on the same butt plate abutting the end of a tang, two rivets, one adjacent each end of the spacer bar, each rivet passing through the spacer bar and a butt plate and attaching the butt plate firmly to the spacer bar, said spacer bar formed with two through bores, one adjacent each end, each tang and each butt plate also formed with a through bore aligning with the through bores at each end of the spacer bar respectively, two screw threaded bolts, one positioned in each of the through bores of the spacer bar and passing through a tang end and a butt plate, two nuts and two washers, one of each on each of the bolts whereby a fuse link provided with a through bore in each end is attached spanning the space

between the tang ends and means for positioning and securing the assembly in a cartridge.

4. A fuse strip carrier and knife blade assembly, including, in combination, a spacer bar of insulating material, two metallic knife blades, one at each end of the spacer bar, each knife blade formed of two rectangular portions one narrower than the other forming a tang end a shoulder, one tang endlapping over one end of the spacer bar and the other tang endlapping over the other end of the spacer bar, metallic butt plates, one at each end of the spacer bar interposed between the tang end of a knife blade and the spacer bar, each butt plate formed with a flat plate portion contacting a tang end on one side and the spacer bar on the other, said butt plates each having two right angle portions, one at each end, one right angle portion directed in one direction, and the other right angle portion in an opposite direction, one right angle portion on one butt plate abutting the end of the spacer bar and the other right angle portion on the same butt plate abutting the end of a tang, two rivets, one adjacent each end of the spacer bar, each rivet passing through the spacer bar and a butt plate and attaching the butt plate firmly to the spacer bar, said spacer bar formed with two through bores, one adjacent each end, each tang and each butt plate also formed with a through bore aligning with the through bores at each end of the spacer bar respectively, two screw threaded bolts, one positioned in each of the through bores of the spacer bar and passing through a tang and a butt plate, two nuts and two washers, one of each on each of the bolts whereby a fuse link provided with a through bore in each end is attached spanning the space between tang ends, a metallic cup formed with a through slot, said slot embracing one of the tang ends between the adjacent butt plate and the adjacent shoulders on the knife blade, said cup formed with a screw thread on a portion of its periphery adapted to engage an internal screw thread in a cartridge fuse end ferrule, said cup further formed with a through slot, said last mentioned slot surrounding the last mentioned tang end and interposed between the cup and the last mentioned butt plate and covering the said vent bores, said cup further formed with an end wall extending beyond the external diameter of said screw threaded portion a distance sufficient to lie beyond the outer periphery of a cartridge end ferrule with which it is associated, the peripheral portion of the said end wall being knurled whereby a non-slipping hand grip is provided, and means associated with the other tang end for co-operation with a cartridge end ferrule positioned on the opposite end of a cartridge from that with which the said metallic cup cooperates.

LEWIS DETCH.
